United States Patent Office

Des. 208,674

Patented Sept. 19, 1967

208,674

SEWING MACHINE STAND

William T. Maxant, Ayer, Mass. 01432

Filed Sept. 23, 1965, Ser. No. 87,140

Term of patent 14 years

(Cl. D33—12)

FIG. 1 is a perspective view of a sewing machine stand illustrating the invention;

FIG. 2 is an end elevation thereof.

The essential features of the invention are those illustrated in full lines in the drawings.

I claim:

The ornamental design for a sewing machine stand, substantially as shown and described.
